(57) **CLAIM**

The ornamental design for a fixed blade knife, as shown and described.

DESCRIPTION

FIG. 1 is a left perspective view of the fixed blade knife embodying the new design;

FIG. 2 is a right side elevation view of the fixed blade knife;
FIG. 3 is a left side elevation view of the fixed blade knife;
FIG. 4 is a top side elevation view of the fixed blade knife;
FIG. 5 is a bottom side elevation view of the fixed blade knife;

FIG. 6 is a front side elevation view of the fixed blade knife; and,

FIG. 7 is a rear side elevation view of the fixed blade knife. The broken lines in the drawings represent portions of the fixed blade knife that form no part of the claimed design.

1 Claim, 5 Drawing Sheets
